(57) **CLAIM**

The ornamental design for a hanger, as shown and described.

DESCRIPTION

FIG. 1 is an oblique perspective view of an hanger showing our new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan thereof.

In all figures, solid line shading is used to better illustrate the three-dimensional ornamental features of the design.

The lightweight broken lines are included are included to show unclaimed subject matter and to delimit claimed solid line portions of the design from unclaimed subject-matter.

1 Claim, 4 Drawing Sheets(56)
